LASTING MACHINE

Jacob S. Kamborian, West Newton, Mass.

Application July 27, 1943, Serial No. 496,267

12 Claims. (Cl. 12—14)

This invention relates to the manufacture of shoes and more particularly to a machine for lasting the heel and forepart portions.

In lasting shoe uppers in accordance with good shoe making practice, the uppers are pulled snugly about the last and held under tension while the marginal portion or lasting allowance is wiped in and secured to the marginal portions of the insole structure, thereby insuring conformity of the upper about the last. Such a procedure, if performed by hand, requires the exercise of considerable skill, and when, as is customary, a lasting machine is employed, the usual prior machine embodies a relatively expensive and complicated mechanism, the use of which requires a skilled operator.

The principal object of the present invention is to provide a lasting machine which is of relatively simple construction and which is reliable and efficient in operation, being capable of exerting and maintaining the required tension on the upper while the lasting allowance is being wiped in and secured in place, thereby insuring the desired conformity of the upper about the last.

Further objects relate to various features of construction and will be apparent from a consideration of the following description and by reference to the accompanying drawings in which:

Fig. 1 is a side elevation of a preferred form of lasting machine constructed in accordance with the present invention;

Fig. 2 is a fragmentary side elevation, similar to Fig. 1, but showing certain parts removed;

Fig. 3 is a section on the line 3—3 of Fig. 1;

Fig. 4 is a section on the line 4—4 of Fig. 1;

Fig. 5 is an enlarged longitudinal section through the wiper operating mechanism;

Fig. 6 is a section on the line 6—6 of Fig. 5;

Fig. 7 is a plan view of the cam embodied in the operating mechanism of Fig. 5;

Fig. 8 is an enlarged perspective view, with the parts shown in section, of the mechanism for applying pressure to the wipers during the wiping-in operation;

Fig. 9 is a fragmentary elevational view illustrating a modified form of the invention; and

Fig. 10 is a side elevation showing a simplified form of the invention, particularly suitable for lasting the forepart of a shoe.

In accordance with the present invention a shoe upper and insole are assembled about a last and a layer of suitable cement is then applied to the lasting allowance and corresponding marginal portions of the insole in the usual manner.

The assemblage is then positioned in a lasting machine of the present invention comprising a support constructed and arranged so as to hold the assembled upper and last with the insole and lasting allowance disposed uppermost in a substantially horizontal position so that the side portions and lasting allowance of either the forepart or heel portion may be substantially simultaneously acted upon by pressure members and wipers, conjointly effective to draw the upper more tightly about the last and wipe in the lasting allowance. To this end the pressure members are mounted at an inclined angle on each side of the support and are relatively movable thereto, and the wipers are mounted on a head or other suitable supporting means which is likewise movable relative to the support, the pressure members and wipers being interconnected with a suitable operating mechanism effective to bring the wipers into operative position and substantially simultaneously actuate the pressure members. In addition, the machine may also include an actuating mechanism responsive to the operation of the wipers for effecting a downward movement of the supporting head or otherwise acting on the wipers so as to cause them to exert an additional pressure on the marginal portions of the upper as they are being wiped in.

Referring to Figs. 1 to 8, the embodiment shown therein comprises a bench or stand 1 having a top 2 positioned at a convenient height for the operator and which carries an adjustable support 3 and associated set screw 4, the support 3 having a spindle 5 or other suitable means for firmly holding a last L with an assembled shoe upper U and insole I (Fig. 4) thereon, as shown more clearly in Figs. 1 and 4. Mounted on each side of the support 3 is a fixed sleeve 6 which constitutes a guide for an elongate slide 7 on whose upper end there is mounted an adjustable pad or cushion 8 engageable with the quarter or rear portion of the upper U, as illustrated in Fig. 4. As shown (Fig. 4) the longitudinal axis of the slide is so inclined as to make an acute angle with that portion of the surface of the shoe upper which is engaged by the pad. The lower end of each pressure member is formed so as to provide a follower 10 engageable with a cam 11 which is carried by one end of a rotatable shaft 12 mounted in a bearing 14 fixed to the top 2. The construction and arrangement of parts are such that when the shafts 12 are rotated through an angle of the order of 90°, the cams 11 act on the pressure members 7 to bring their cushioned ends 8 into engagement with the

sides of the upper and thus to exert an upward stress on the upper such as to draw the upper upwardly and tightly about the last.

The rear of the top 2 supports an upwardly and forwardly extending neck 15 formed with a vertically extending dovetailed groove 16 (Fig. 3) which receives the vertical wall 18 of an L-shaped head 20 and slidably supports the same for movement toward and away from the support 3. The rear face of the wall 18 carries a laterally extending bracket 22, the outer end of which is pivotally connected to the upper end of a vertically extending actuating rod 24 slidably mounted in sleeves 25 and 26 suitably secured to the neck 15 and stand 1, respectively. Tension springs 28 and 29 cooperate normally to hold the head 20 and rod 24 in their uppermost position so that the head 20 is disposed a few inches above the last, as illustrated in Fig. 1. The lower end of the rod 24 is connected through a link 30 to a treadle 31 in conventional manner, the construction and arrangement being such that when the treadle is depressed by the operator's foot, the head 20 is lowered to operative position relatively to the last L. Crank arms 32 connect the shafts 12 with a collar 33 carried by the rod 24 so that downward movement of the rod operates the pressure member 7 simultaneously with the lowering of the head 20.

A pair of electrically heated wipers 34, 35 is mounted on the under side of the head 20, the inner ends of the wipers being pivoted to a cross-link 36 which carries an upwardly projecting stud 38 slideable in a slot 39 formed in the head 20, as shown in Fig. 3. The opposite ends of the wipers carry upwardly projecting studs 40 which ride in arcuate slots 41 formed in the head 20, the parts being so designed that when the stud 38 is moved forwardly, the cross-piece 36 and studs 40 cooperate to move the wipers.

Movement of the stud 38 and hence the operation of the wipers 34, 35 is controlled by the mechanism illustrated in Fig. 5 to 7, comprising a cam 50 (Fig. 7) formed with a groove 51 which receives the upwardly projecting end of the stud 38, the groove 51 being so designed that one complete revolution or operating cycle of the cam is effective to reciprocate the stud in slot 39. The cam 50 is screwed or otherwise suitably secured to a one-revolution clutch mechanism 55 (Fig. 5) which is coupled with the drive shaft 57 of either a slow speed motor or a back-gear motor 58 suitably mounted on the wall 18.

The mechanism 55 comprises a sleeve-like member 60 which receives a shaft 57 and is formed with flange ends 61 and 62, the bore at the lower end of the sleeve being enlarged to receive a thrust bearing 64 by means of which the sleeve is held in assembled relation with the shaft 57 so that the latter may rotate independently of the sleeve and associated parts. Adjacent to its end the shaft 57 is formed with a circumferential slot 66 shaped to provide an abutment 67 horizontally aligned with a transverse opening 68 in the flange 61, as shown in Figs. 5 and 6. A spring-pressed latch finger 70 is pivotally mounted within the opening 68, and one end of the latch extends outwardly so as to be engageable with an abutment 71 formed integral with the flange 61. When the latch 70 swings inwardly under the influence of springs 72 and 73, its locking end 74 is positioned to engage the abutment 67 of the shaft 57 so that the sleeve 60 becomes locked to the shaft 57 to rotate therewith.

Movement of the latch 70 is controlled by a retractile finger 75 slidably mounted in the bore of a sleeve 76 which is of square cross-section and mounted to slide in an opening 76a formed in the head 20. The finger 75 is disposed between the ends of the wipers so as to engage and be retracted by the insole of the shoe being lasted when the head 20 is brought into operative position. A small compression spring 77 (Fig. 5) fitting within the finger 75 and acting on the sleeve 76 through a pin carried by the sleeve and projecting through longitudinally extending slots in the wall of the finger normally holds the finger in extended position. The sleeve 76 is formed with a slot 79 of sufficient size to accommodate the end of latch 70 so that when the sleeve is quickly slid upwardly, the springs 72 and 73 operate to throw the latch into operative engagement with the shaft 57. The sleeve 76 is normally held in lowermost position by a spring 77a mounted within the upper end of a casing 78 which houses the sleeve 76. Upward movement of sleeve 76 is controlled by a spring-pressed latch or dog 80 pivotally mounted in an opening 81 (Fig. 5) in the sleeve, the inner end of the dog being engageable with the upper end of finger 75 and the outer end being engageable with a trip 82 secured to the flange 62. The construction and arrangement of parts are such that when the finger 75 moves upwardly it carries the sleeve upwardly by engagement with the dog 80 a distance sufficient to permit the latch 70 to operate in the aforesaid manner, whereupon the outer end of the dog 80 engages the trip 82 to effect disengagement of the finger 75 and dog 80, thus restoring the sleeve 76 to the action of spring 77a which is effective to move the sleeve 76 downwardly to the position shown in Fig. 5. The elevation of the sleeve 76 permits the sleeve 60 and associated parts to rotate through one revolution, it being noted that when the sleeve 76 moves back to normal position, its upper end portion provides, in effect, a stop arresting further rotation of the sleeve 60, as shown in Fig. 6. One revolution of the sleeve 60 is effective to cause the wipers 34, 35 to make one operating movement in the manner previously explained.

In order to impart an additional pressure on the wipers, the mechanism illustrated in Fig. 8 may be employed, this mechanism comprising a rack 90 rigidly secured to the neck 15 so as to mesh with a gear 91 carried by one end of a shaft 92 which is rotatably mounted in a bracket 93 integral with the rear wall 18, the construction and arrangement being such that rotation of the shaft 92 in a counterclockwise direction, as viewed in Fig. 8, lowers the head 20 and associated parts. Rotation of the shaft 92 is controlled by the cam 50 acting through a mechanism which includes a ratchet 96 formed on the end of shaft 92 and operatively associated with a pawl 97 eccentrically mounted on the side of a collar 98 which is freely rotatable on shaft 92. One end of a small tension spring 100 is connected to the periphery of the collar 98 and its opposite end is fixed to the lower end of the wall 18, this spring being effective yieldingly to hold the collar in the position shown in Fig. 8. The periphery of the collar is shaped so as to oppose clockwise rotation, but to permit counterclockwise rotation through an angle of 90° to 180°. The pawl 97 is formed with a depending tail 101 engageable by the end of a plunger rod 102 which is slidably mounted in a sleeve 103 carried by the head 20. A compression spring 104, acting

on a collar 105 carried by the rod 102, normally holds the latter in retracted position relative to the pawl 97. The opposite end of the rod 102 is provided with a follower 106 engageable with the periphery of cam 58 which is formed with a throw or rise element 108, the design being such that the rise 108 comes into action when the wipers 34, 35 are approaching the limit of their wiping-in movement. Thus, the cam 58 acts on the rod 102, through ratchet and pawl 96, 97 and collar 98, to rotate the shaft 92 through an angle of about 90°, thereby effecting a slight downward movement of the head 20 which causes a downward pressure to be exerted by the wipers 34, 35 on the lasting allowance being acted upon, in addition to the pressure being applied by reason of the operation of the treadle 31.

A resumé of the operation of the machine is as follows: A last L with an assembled upper U and insole, provided with a layer of cement along their marginal portions, is first mounted on the spindle 5 in alignment with the wipers 34, 35 which, if desired, may be heated to the desired temperature by proper adjustment of the rheostat 110 (Fig. 1). With the motor 58 turned on and the support properly adjusted, the operator then depresses the treadle 31 which not only brings the wipers downwardly to operative position and simultaneously actuates the pressure members 7, but also initiates operation of the wipers by retraction of the finger 78 which contacts the insole on the last L, as above explained. As the wipers approach their limit of inward wiping-in movement, the cam 58 operates, as above explained, to effect a further downward movement of the head 20 and associated parts which causes the wipers to exert an additional pressure on the wiped-in portions of the upper. Upon release of the treadle, the pressure members 7 are released and all parts are restored to normal position by the springs 28, 29 preparatory to lasting another shoe.

It will be noted that during the above-described operation the shoe upper is subjected substantially simultaneously to the action of the pressure members 7 which draw the upper upwardly more tightly about the last, the wiping-in action of the wipers 34, 35 and an added downward pressure exerted by the wipers as they approach the limit of their wiping-in movement. Thus, the lasting allowance is wiped in under pressure as the upper is being drawn upwardly and held firmly about the last, and hence a high degree of conformity of the upper about the last is secured.

The lasting machine illustrated in Fig. 9 is substantially identical in all material particulars to that of the embodiment shown in Figs. 1 to 8, except that the vertically moving head 20^a is provided with lateral extensions 115 which operate the pressure members 7 by engagement with arms 116 pivotally connected to supports 118 fixed to the top 2. The arms 116 act through springs 120 on similar arms 121 pivotally mounted on supports 118 so as to yieldingly urge their lower ends inwardly against the followers 10^a of the pressure members 7. Thus, as the head 20 descends, the pressure members 7 are operated by a yielding pressure exerted by springs 120, as distinguished from the relative non-yielding pressure exerted by the cams 11 of the previously described embodiment. In all other respects the mechanism may be identical to that previously described.

The lasting machine shown in Fig. 10 provides

a simplified arrangement for lasting the forepart of a shoe, and with the exception of the support and associated parts, the mechanism may be identical to that of the embodiment of Figs. 1 to 8, the same or similar reference characters being applied to corresponding parts. In this embodiment the adjustable support 3^a comprises an upstanding member having a padded end 123 shaped to receive the forepart of the shoe so that it may be firmly held by the operator during the lasting operation. The lasting operation is substantially the same in that the last L and shoe upper U are firmly held in correct position on the support 3^a, and the treadle is then operated to bring the head 20 and associated parts into operative position in the manner previously explained.

While I have shown and described different desirable embodiments of the invention, it is to be understood that this disclosure is for the purpose of illustration, and that various changes in shape, proportion and arrangement of parts, as well as the substitution of equivalent elements for those herein shown and described, may be made without departing from the spirit and scope of the present invention as set forth in the appended claims.

I claim:

1. A lasting machine comprising a support for a last with an assembled upper and insole thereon, two slides disposed one at each side respectively of the support, a rigid guide for each slide, an upper-engaging pad secured to the upper end of each slide, the guides defining upwardly convergent paths for the slides, said paths making acute angles with the surface of the upper with which the pads contact whereby upward movement of the slides stresses the upper upwardly about the last, wipers relatively movable toward and away from said support and operative to wipe in the marginal portions of said upper over the insole, and means constructed and arranged to effect a substantially simultaneous relative movement between said support and pressure members and also said support and wipers so that said pressure members act on said upper as said wipers operate to wipe in said marginal portions.

2. A lasting machine comprising a support for holding a last with an assembled upper and insole thereon so that the insole and adjacent parts of the upper are disposed uppermost in a substantially horizontal position, two slides disposed one at each side respectively of the support, a rigid guide for each slide, an upper-engaging pad secured to the upper end of each slide, the guides defining upwardly convergent paths for the slides, said paths making acute angles with the surface of the upper with which the pads contact whereby upward movement of the slides stresses the upper upwardly about the last, a head slidably mounted to move toward and away from said support, wipers carried by said head and arranged to wipe in the marginal portion of the rear of said upper, mechanism for lowering said head and substantially simultaneously effecting the engagement of the pressure members with said upper, and actuating means for operating said wipers when said head descends to a predetermined level.

3. A lasting machine comprising a support for holding a last with an assembled upper and insole thereon so that the insole and adjacent parts of the upper are disposed uppermost in a substantially horizontal position, pressure members slidably mounted at an upwardly inclined angle

relative to said support with their upper end portions engageable with the opposite sides of the heel portion of said upper so as to urge the upper more tightly about the last, a head slidably mounted to move toward and away from said support, wipers carried by said head and arranged to wipe in the marginal portion of the rear of said upper, mechanism for lowering said head and substantially simultaneously effecting the engagement of the pressure members with said upper, actuating means for said wipers, and a retractile finger associated with said actuating means and operative upon being retracted to effect the operation of said actuating means, said finger being retractile by engagement with said insole when said head moves downwardly to bring said wipers into operative position.

4. A lasting machine comprising a support for a last with an assembled upper and insole thereon, a head slidably mounted to move toward and away from said support, wipers carried by said head and operative to wipe in the marginal portions of the upper over the insole, actuating means for said wipers carried by said head, mechanism for lowering said head to bring said wipers into operative position, means operative when said wipers are lowered to operative position to effect the operation of said actuating means, and means responsive to the operation of said actuating means for effecting a downward movement of said head so as to cause said wipers to exert a downward pressure against the marginal portions of the shoe upper simultaneously with the wiping in operation.

5. A lasting machine comprising a support for a last with an assembled upper and insole thereon, pressure members relatively movable toward and away from said support so as to engage the opposite side portions of the upper and act thereon at such an angle as to urge the upper more tightly about the last, wipers relatively movable toward and away from said support and operative to wipe in the marginal portions of said upper over the insole, means constructed and arranged to effect a substantially simultaneous relative movement between said support and pressure members and also said support and wipers so that said pressure members act on said upper as said wipers operate to wipe in said marginal portions, and means responsive to the operation of the wiper operating means for effecting a downward movement of said wipers so as to cause said wipers to exert a downward pressure against the marginal portions of the shoe upper simultaneously with the wiping in operation.

6. A lasting machine comprising a support for a last with an assembled upper and insole thereon, pressure members relatively movable toward and away from said support so as to engage the opposite side portions of the upper and act thereon at such an angle as to urge the upper more tightly about the last, wipers relatively movable toward and away from said support and operative to wipe in the marginal portions of said upper over the insole, mechanism operative to effect relative movement between said pressure members and support and substantially simultaneously effect relative movement between said wipers and support thereby to cause said pressure members to act on said shoe upper during the operation of said wipers, and means responsive to the operation of the wiper operating mechanism for effecting a downward movement of said wipers so as to cause said wipers to exert a down-

ward pressure against the marginal portions of the shoe upper simultaneously with the wiping in operation.

7. A lasting machine comprising a fixed support for holding a last with an assembled upper and insole thereon, pressure members mounted to move toward and away from said support and having end portions engageable with the sides of said uppers so as to urge the upper more tightly about the last in response to downward movement toward said support, wipers mounted to move toward and away from said support and operative in response to movement toward said support to wipe in the marginal portions of said upper over the insole, and mechanism associated with said pressure members and wipers for effecting substantially simultaneous operation thereof, and means responsive to the operation of the wiper operating mechanism for effecting a downward movement of said wipers so as to cause said wipers to exert a downward pressure against the marginal portions of the shoe upper simultaneously with the wiping in operation.

8. A lasting machine comprising a fixed support for holding a last with an assembled upper and insole thereon so that the insole and adjacent parts of the upper are disposed uppermost in a substantially horizontal position, pressure members slidably mounted at an upwardly inclined angle relative to said support with their upper end portions engageable with the opposite sides of the heel portion of said upper so as to urge the upper more tightly about the last, a head slidably mounted to move toward and away from said support, wipers carried by said head and arranged to wipe in the marginal portion of the rear of said upper, mechanism for lowering said head and substantially simultaneously effecting the engagement of the pressure members with said upper, actuating means for operating said wipers when said head descends to a predetermined level, and means responsive to the operation of said actuating means for effecting a downward movement of said head so as to cause said wipers to exert a downward pressure against the marginal portions of the shoe upper simultaneously with the wiping in operation.

9. A lasting machine comprising a fixed support for holding a last with an assembled upper and insole thereon so that the insole and adjacent parts of the upper are disposed uppermost in a substantially horizontal position, pressure members slidably mounted at an upwardly inclined angle relative to said support with their upper end portions engageable with the opposite sides of the heel portion of said upper so as to urge the upper more tightly about the last, a head slidably mounted to move toward and away from said support, wipers carried by said head and arranged to wipe in the marginal portion of the rear of said upper, mechanism for lowering said head and substantially simultaneously effecting the engagement of the pressure members with said upper, actuating means for said wipers, and a retractile finger associated with said actuating means and operative upon being retracted to effect the operation of said actuating means, said finger being retractile by engagement with said insole when said head moves downwardly to bring said wipers into operative position, and means responsive to the operation of said activating means for effecting a downward movement of said head so as to cause said wipers to exert a downward pressure against the marginal portions

of the shoe upper simultaneously with the wiping in operation.

10. In a lasting machine of the class described, having a support for holding a last with an assembled shoe upper and insole thereon, a head mounted to move toward and away from said support, wipers mounted on said head for wiping in the lasting allowance of the upper over the insole, and means operative to actuate said wipers when said head moves into operative position relative to said support, said means comprising a motor, clutch mechanism connecting said motor and wipers, and a retractible finger operatively connected with said clutch mechanism and effective upon being retracted to operate said clutch mechanism, said finger projecting outwardly from said head and being engageable with and retractible by the insole when said head moves into operative position.

11. In a lasting machine of the class described, having a support for holding a last with an assembled shoe upper and insole thereon, a head mounted to move toward and away from said support, wipers mounted on said head for wiping in the lasting allowance of the upper over the insole, means operative to actuate said wipers when said head moves into operative position relative to said support, said means comprising a motor, clutch mechanism connecting said motor and wipers, and a retractible finger operatively connected with said clutch mechanism and effective upon being retracted to operate said clutch mechanism, said finger projecting outwardly

from said head and being engageable with and retractible by the insole when said head moves into operative position, and means responsive to the operation of the wiper actuating means for effecting a further movement of said head toward said support so as to cause said wipers to exert a pressure against the marginal portions of the shoe upper simultaneously with the wiping in operation.

12. In a lasting machine of the class described, having a support for holding a last within an assembled shoe upper and insole thereon, a head mounted to move toward and away from said support, wipers mounted on said head for wiping in the lasting allowance of the upper over the insole, means operative to actuate said wipers when said head moves into operative position relative to said support, pressure members slidably mounted at an inclined angle relative to said support with their inner end portions engageable with the sides of the upper, connections between said pressure members and head effective as said head is moved toward operative position to slide said pressure members toward said support so as to urge the upper more tightly about the last during the wiping in operation, and means responsive to the operation of the wiper actuating means for effecting a further movement of said head toward said support so as to cause said wipers to exert a pressure against the marginal portions of the shoe upper simultaneously with the wiping in operation.

JACOB S. KAMBORIAN.
